UNITED STATES PATENT OFFICE

115,079

DESIGN FOR EMBROIDERED TEXTILE FABRIC OR SIMILAR ARTICLE

Dan Rubenberg, New York, N. Y., assignor to Rubenberg Silk Company, Inc., New York, N. Y.

Application January 9, 1939, Serial No. 82,236

Term of patent 3½ years

To all whom it may concern:

Be it known that I, Dan Rubenberg, a citizen of the United States, residing at 100 Riverside Drive, in the Borough of Manhattan, city of New York, in the county of New York, and State of New York, have invented a new, original, and ornamental Design for Embroidered Textile Fabric or Similar Article, of which the following is a specification, reference being had to the accompanying drawing, forming part thereof.

The figure is a plan view of a piece of embroidered textile fabric or similar article, showing my new design.

I claim:

The ornamental design for embroidered textile fabric or similar article, as shown.

DAN RUBENBERG.
